UNITED STATES PATENT OFFICE

142,795

DESIGN FOR AN INSULATED CONTAINER FOR BOTTLES

Peter Schlumbohm, New York, N. Y.

Application April 23, 1945, Serial No. 119,154

Term of patent 14 years

(Cl. D58—8)

To all whom it may concern:

Be it known that Peter Schlumbohm, a citizen of the German Republic, residing at New York, in the county of New York and State of New York, has invented a new, original, and ornamental Design for an Insulated Container for Bottles, of which the following is a specification, reference being had to the accompanying drawing, forming part thereof.

Fig. 1 is a side elevational view of an insulated container for bottles showing my new design.

Fig. 2 is a top view of Fig. 1.

Fig. 3 is a bottom view of Fig. 1.

I claim:

The ornamental design for an insulated container for bottles, as shown.

PETER SCHLUMBOHM.
